UNITED STATES PATENT OFFICE

WALTER K. BURGESS, OF SANTA MONICA, CALIFORNIA

SUPERCHARGER STRUCTURE

Application filed February 3, 1928. Serial No. 251,816.

This invention relates to a turbine air compressor and supercharger for internal combustion engines, and has for its object to provide a device of this class which is particularly simple in construction, positive and efficient in operation, light in weight, strong and durable.

With this object in view, the invention consists of the employment of an impeller rotatable within a casing and the application of a double Venturi system, which in connection with certain improvements for effecting a piston tight seal between the impeller and the casing, assists in complete vaporization 15 of the liquid fuel, and increases the compression of the gas to a high point of efficiency.

The invention further consists of certain other details of construction and combinations of parts, all of which will be first fully 20 described and afterwards specifically pointed out in the appended claims.

Referring to the accompanying drawings:

Fig. 1 is a side elevation partly in vertical section of the device constructed in accordance with my invention.

Fig. 2 is a vertical transverse sectional view partly in elevation of the device, and

Fig. 3 is a transverse sectional view through one of the blades of the impeller.

Like numerals of reference indicate the same parts throughout the several figures, in which:

1 indicates the device, which includes the impeller 2 and casing 3, which casing is composed of two sections 4 and 5 having flanges 6 bolted together at 7. As shown in Fig. 1, the casing 3 is provided with a tangential outlet 8, flanged at 9 to receive a check valve or other fitting as may be desired.

40 The central portion of the casing portion 5, is provided with a true Venturi opening 10, to which a carburetting device may be attached in any approved manner.

Centrally of the complementary casing portion 4 is a housing 11, threaded at 12 to receive a packing nut 13.

Within said housing 11, I dispose two ball-bearing races 14 and 15, spaced apart by a bearing-spacer 16, while against each of said

50 races 14 and 15, I provide a felt washer 17

to be compressed by the packing nut 13 to provide an oil tight assembly.

Connected to the housing 11, is an oil feed line 18, preferably from the oil pressure system of the motor to which the device is attached, while the bearing spacer 16 is perforated to permit oil under pressure from the feed line 18 to enter within the spacer 16, which forms an oil chamber 19.

The impeller 2 includes a plurality of radial 60 blades 20, radiating from a hub 21, mounted on a hollow drive shaft 22 running on the bearings 14 and 15, which shaft is perforated at 23 to receive oil from the oil chamber 19 within the same. Connecting with the said hollow shaft 22 are oil ports 24 disposed in the impeller blades near each edge thereof, as shown in Fig. 3, while the actual edges of 65 said blades are provided with a V shaped oil groove 25 which communicates with the said oil ports 24 at predetermined points as shown in Fig. 2.

The casing 3 is shaped to form an annular tubular-like chamber 26 at its outer extremity, while the same is sharply reduced at 27 to provide a Venturi formation immediately adjacent to and opening into said tubular-like chamber 26.

The blades 20 of the impeller 2 are formed to closely conform to the shape of the casing and preferably so as to provide a clearance of not more than .006", though those portions of the impeller blades 20 immediately adjacent the outer venturi 10 are formed with straight vertical edges 28, so as to provide ample spaces between the impeller blades 20 to receive the gas passing through the said venturi 10.

Having thus described the invention its operation is as follows:

The gas passing through the venturi 10 is accelerated and enters the chambers formed between the blades 20 of the impeller 2. By centrifugal force, the gas is forced through the second venturi 27 where it is further accelerated and enters the tubular-like chamber 26, and is here compressed by centrifugal force.

This additional Venturi action on the gas and its compression, creates a minus pressure

in the impeller adjacent the outer venturi 10, and increases the acceleration of the gas passing through said outer venturi 10 and into the impeller 2.

5 The effective compression of the gas and efficiency of the entire device is increased by the oil seal which is established within the V shaped grooves 25 in the edges of the impeller blades 20, which oil seal is effectively maintained by the oil pressure from the oil line 18 augmented by centrifugal force carrying the oil from the oil chamber 19 outwardly through the oil ports 24 and into the V shaped oil grooves 25.

10 By this construction, a piston-tight seal is established and effectively maintained, so that the highest degree of efficiency is obtained in operation. The gas thus compressed and vaporized under the influence of the rotating impeller is delivered to the outlet 8 together with such excess oil as may escape from the oil seals, which oil is carried to the motor for lubricating purposes as will be fully understood by those skilled in the art. In 15 order to relieve the device from excess temperature due to friction and compression, I prefer to provide the casing 3 with radiating fins 3'.

15 While I have shown and described a preferred embodiment of the invention, I do not wish to be understood as limiting myself to the exact construction herein set forth, as I consider myself clearly entitled to all such changes and modifications as fall within the 20 limit and scope of the appended claims.

What I claim as new and desire to secure by Letters Patent of the United States, is:

1. A device of the character described including a rotatable impeller, a casing for said impeller, the said casing being centrally provided with a Venturi opening, and tangentially provided with an outlet, the said casing also including an annular tubular-like chamber at the extremity thereof and a Venturi 25 shaped portion communicating with said tubular-like chamber, a housing including a oil chamber, a hollow shaft to receive oil from said oil chamber, the blades of said impeller closely conforming to the formation of the said casing and provided with oil ports to receive oil from said hollow shaft, the edges of said blades being provided with an oil-seal groove in communication with the said oil ports.

2. A device of the character described including a rotatable impeller, a casing for said impeller, the said casing being centrally provided with a Venturi opening, and tangentially provided with an outlet, the said casing also including an annular tubular-like chamber at the extremity thereof and a Venturi shaped portion communicating with said tubular-like chamber, a housing including an oil chamber, a hollow shaft to receive oil from said oil chamber, the blades of said impeller

70 closely conforming to the formation of said casing, and provided with means for receiving oil from the hollow shaft to establish an oil seal at the edges of said blades.

3. A device of the character described, including a rotatable impeller, a casing for the impeller, said casing being centrally provided with a Venturi opening and tangentially provided with an outlet, said casing also including an annular tubular-like chamber at the extremity thereof and a Venturi shaped portion communicating with said tubular-like chamber, a housing including an oil chamber, the blades of the impeller closely conforming to the formation of the said casing and provided with means for receiving oil from the oil chamber to establish an oil seal at the edges of said blades.

4. A device of the character described including a rotatable impeller, a casing for said impeller, the casing being centrally provided with a Venturi opening, and tangentially provided with an outlet, the said casing also including an annular tubular-like chamber at the extremity thereof and a Venturi shaped portion communicating with said tubular-like chamber, the blades of the impeller closely conforming to the formation of the said casing, and provided with means to receive oil to establish an oil seal at the edges of said blades.

5. A device of the character described including a rotatable impeller, a casing for said impeller, said casing being centrally provided with an inlet opening and tangentially provided with an outlet, the said casing also including an annular chamber at the extremity thereof and a Venturi shaped portion communicating with said annular chamber, the blades of said impeller closely conforming to the formation of the casing and provided with means for establishing an oil seal at the edges of the said blades.

In testimony whereof I affix my signature.

WALTER K. BURGESS, 1st Lt. A. C.
